UNITED STATES PATENT OFFICE.

WILLIAM M. SMITH, OF WEST MERIDEN, CONNECTICUT, ASSIGNOR TO
MERIDEN BRITANNIA COMPANY, OF SAME PLACE.

DESIGN FOR COFFIN-HANDLES.

Specification forming part of Design No. 7,914, dated December 22, 1874; application filed October 31, 1874.
[Term of Patent 7 years.]

CASE C.

To all whom it may concern:

Be it known that I, WILLIAM M. SMITH, of West Meriden, in the county of New Haven and State of Connecticut, have invented a new Design for Coffin-Handle; and I do hereby declare the following, when taken in connection with the accompanying drawings and the letters of reference marked thereon, to be a full, clear, and exact description of the same, and which said drawings constitute part of this specification, and represent a front view of one socket and part of the handle.

This invention relates to a design for handle and socket for coffins; and consists in the peculiar configuration, as hereinafter described, and shown in the accompanying illustration.

The socket is in representation of a banner, A, hanging from a roll, B, the lower edge of the banner indented. On the face of the banner is the lug C, which forms the bearing for the handle. D is the handle-bar, and E the lever.

What I claim is—

The design for handle-socket, consisting of the banner-shaped base with the lug C thereon, as shown and described.

WILLIAM M. SMITH.
